UNITED STATES PATENT OFFICE

118,245

DESIGN FOR A SCOOTER FOOTBOARD OR SIMILAR ARTICLE

John Gordon Rideout, Cleveland, Ohio, assignor to Junior Toy Corporation, Hammond, Ind.

Application June 8, 1939, Serial No. 85,399

Term of patent 14 years

To all whom it may concern:

Be it known that I, John Gordon Rideout, a citizen of the United States, residing at Cleveland, in the county of Cuyahoga and State of Ohio, have invented a new, original, and ornamental Design for a Scooter Footboard or Similar Article, of which the following is a specification, reference being had to the accompanying drawing, forming part thereof.

Fig. 1 is a perspective view of a scooter footboard or similar article showing my new design.

Fig. 2 is a side elevational view thereof.

Fig. 3 is a top plan view.

I claim:

The ornamental design for a scooter footboard or similar article, substantially as shown.

JOHN GORDON RIDEOUT.
